UNITED STATES PATENT OFFICE.

FREDRICK R. MORTON, OF FRESNO, CALIFORNIA.

ROAD SCRAPER.

1,419,642.

Specification of Letters Patent. Patented June 13, 1922.

Application filed July 21, 1921. Serial No. 486,497.

To all whom it may concern:

Be it known that FREDRICK R. MORTON, a citizen of the United States, residing at Fresno, in the county of Fresno and State 5 of California, has invented certain new and useful Improvements in Road Scrapers, of which the following is a specification.

My invention relates to machines for scraping, digging, or leveling earth, roads 10 or the like, and has particular reference to improvements in scrapers shown in my co-pending application, Serial No. 460,274, filed April 11, 1921.

An important object of the invention is to 15 provide simplified means for effecting the forward and upward movement of the supplemental frame, for elevating the scraper.

A further object of the invention is to 20 provide means whereby the pull for elevating the scraper is transmitted directly to the ends of the scraper, and the scraper is free from the downward pressure, which would otherwise occur at the front of the main frame, if the cable is drawn over an 25 elevated pulley.

A further object of the invention is to 30 provide means for tilting the scraper upon its longitudinal axis, in a rearward direction, whereby the load may be carried there- by, without liability of spilling.

In the accompanying drawings forming a part of this specification, and in which like numerals are employed to designate like parts throughout the same,

35 Fig. 1 is a plan view of a machine embodying my invention,

Fig. 2 is a side elevation of the same, parts being shown in section,

40 Fig. 3 is a side elevation of the elevating track and associated elements,

Fig. 4 is an enlarged detail section taken on line 4—4 of Figure 1,

Fig. 5 is a similar view taken on line 5—5 of Figure 1,

45 Fig. 6 is an end elevation of the machine,

Fig. 7 is a detail section taken on line 7—7 of Figure 1,

Fig. 8 is a similar view taken on line 8—8 50 of Figure 1,

Fig. 9 is a transverse section taken on line 9—9 of Figure 8,

Fig. 10 is a transverse section taken on line 10—10 of Figure 3.

55 In the drawings, wherein for the purpose of illustration is shown a preferred em-

bodiment of my invention, the numeral 15 designates a main frame, as a whole, embodying longitudinal beams 16, having forward converging portions 17. The beams 60 16 are connected by transverse beams 18' and 19. The forward ends of the converging portions 17 are connected by a guide housing 21, and are rigidly attached to the rearwardly diverging arms 22 (Figure 2) 65 of this guide housing. The guide housing 21, see particularly Figs. 8 and 9, has a pair of upstanding arms 23, and a pair of depending arms 24, preferably rigidly secured thereto. Arranged between the arms 70 23 is a roller or wheel 25, carried by a bolt 26, adapted to be inserted in selected vertically spaced openings 27. A roller or wheel 28 is arranged between the arms 24, and is carried by a bolt 29 or the like, for 75 insertion within vertically spaced openings 30. By this means the rollers may be raised and lowered within their arms, and secured thereto in adjustment. A draw-bar 31 extends through the guide housing 21, the top 80 of which is slotted at 21'. This draw-bar 31 has an upper inclined face 31', extending upwardly toward its rear end, as shown. The rollers 25 and 28 engage the opposite faces of the draw-bar. The draw-bar, as 85 will be explained, serves as the supporting means for the forward end of the main frame, and by the angular adjustment of the draw-bar, such forward end may be raised or lowered. 90

The rear end of the main frame 15 is supported by an axle 32, upon which are rotatably mounted wheels 33. The ends of the axle project into openings formed in boxes or castings 35, and are preferably 95 keyed therein, or otherwise secured thereto. These boxes are provided with lower L-shaped flanges 36, which are bolted to the longitudinal beams 16, at 35. These boxes 35 are vertically arranged, and carry pairs 100 of upwardly extending vertical arms 38.

The numeral 39 designates an upper supplemental frame, as a whole, embodying longitudinal beams 40, connected by a transverse beam 41, and a rear transverse beam 105 41'. The rear portions of the beams 40 extend between the arms 38, and are supported by lower rollers 42, arranged between the arms and pivotally connected therewith, while upper rollers 43 engage the top of the beams 40, and are pivoted to the arms 38. There is sufficient play between the beams.

40 and the guide rollers 42 and 43, to permit of the forward end of the supplemental frame 39 being vertically adjusted, as well as moved longitudinally.

5 The numeral 44 designates a pair of tracks, which are rigidly mounted upon the beams 16. Each track embodies an elevated horizontal portion 44', and an inclined or elevating portion 45'. The horizontal portions 44' serve as supports for the supplemental frame 39, engaging the beams 40 thereof, when the supplemental support is in the lowered position.

10 The numeral 45 designates a scraping 15 or digging element as a whole, embodying a bottom 46 and back 47 and ends 48. A cleat 49, Figs. 1, 2 and 10, is bolted to each end 48, near the top of this end, and preferably nearer the back 47 than the front 20 of the end. This cleat carries a shaft or trunnion 50, preferably integral therewith, and the shaft or trunnion is pivotally mounted in an opening 51, in a depending plate or bracket 52, bolted to the longitudinal beam 40. Rotatably mounted upon the shafts or trunnions 50 are wheels 53, held against lateral displacement thereon, and these wheels are arranged to travel upon the tracks 44. It is thus seen that the 25 scraping element is pivotally supported by the shafts 50, and associated elements, and by virtue of the arrangement of these shafts or pivots, when the scraping element contains earth, there is a tendency for the forward end of the scraping element to swing downwardly, but when the scraping element is empty, the rear portion including the back 47 is heavier than the forward portion, and hence swings the forward end upwardly.

30 Means are provided to lock the scraping element 45 against turning movement upon its shafts or pivots 50, including a reciprocating bolt 55, Fig. 4, operating through an opening in a bracket 56, bolted at 57, to the transverse beam 41'. This bolt is adapted to enter an opening 58 formed in a co-acting lock element or plate 59, and bolted to the back 47 near its center. The bolt 55 is pivoted at 60, to a vertically swinging lever 61, pivoted at 62 to a portion of the bracket 56, the lower end of this lever being urged forwardly by a spring 63.

35 Means are provided to lock the forward end of the supplemental frame 39 against vertical movement with relation to the main frame (Figs. 2 and 4) comprising a latch 68 having a hooked end 69, to engage over a roller 70, pivoted upon the transverse bar 41 of the supplemental frame. The latch 68 is pivoted upon the transverse bar 19 of the main frame, to swing in a vertical plane, and is urged forwardly by a retractile coil spring 71, connected therewith, as 40 more clearly shown in Fig. 5. A rope or

cable 72 is attached to the latch 68, near its upper end, and this cable extends rearwardly for connection, at 73, with the lower end of a vertically swinging lever 74, pivoted upon a bar or support 75, secured to the transverse beam 41'. When the upper end of the lever 74 is swung forwardly, the head 69 of the latch 68 will be moved off of the roller 70, and the forward end of the supplemental frame released. 75

The numeral 89 designates a brake lever, Fig. 6, rigidly mounted upon a rock shaft 90, pivoted within brackets 91, fixed to the transverse bars 18'. The rock shaft 90 carries brake shoes 92, arranged to engage 80 with the wheels 33, as shown.

The numeral 93 designates a draft bar, which may be rigidly secured to a tractor, or upon a wheeled support drawn by horses or the like. The draft bar 93 is securely supported against downward displacement, and this draft bar enters the U-shaped head 94 of the draw-bar 31, and is connected therein by a pin or bolt 95. The numeral 96 designates a lever, which is pivoted centrally thereof upon the pin or bolt 95, and is arranged on top of the head 94. Pivotally connected with the ends of the lever 96 are longitudinal pull elements 97, which may be rods, cables, chains or the like. 95 These pull elements extend rearwardly in diverging relation, and are connected with the inner ends of transverse levers 98, as shown at 99. These levers are pivoted at their opposite ends, to the main frame beams 100 16, as shown at 100. Pull elements 101 are pivoted to the levers 98 at 102, between the ends thereof, and extend rearwardly, in diverging relation, for pivotal connection with attaching elements or rods 103. The 105 rear ends of these attaching elements or rods are secured to the ends 48 by bolts 104. The attaching elements 103 are preferably arranged in alignment with the shafts 50, and extend across them. The pull is 110 transmitted directly to the ends 48 of the scraping element, and adjacent to its pivot supports 50.

A pulley 104' (Fig. 2) is pivoted within a bracket 105, secured to the transverse beam 115 19, and this pulley is engaged by a cable 106, passed therebeneath and upwardly and attached to a bracket 107, secured to the beam 41. The pulley 106 serves to draw the forward end of the supplemental frame rearwardly and downwardly. The cable 106 extends forwardly and is connected with a lever 108, at 109, and this lever is pivoted upon a bracket 110, secured to the beam 102. A spring 111 swings the lever 108 forwardly. 120

A cable 112 is secured to the upper end of the lever 74, and this cable extends to a suitable point upon the tractor or the like. A cable 113 is attached to the cable 112, 130

at 114, and the cable 113 extends rearwardly for attachment to the upper end of the lever 61. There is considerable slack in the cable 113, and the pull upon the cable 112 5 will move the lever 74, without and before moving the lever 61.

The operation of the machine is as follows: The entire draft in a forwardly direction is transmitted to the bar 93, and the 10 pull is transmitted to the lever 96. The draft bar 31 being free to move longitudinally the pull is transmitted to the elements 97, levers 98, elements 101, and finally to the ends of the scraping element. This pull is 15 then transmitted to the shafts 50, to the supplemental frame, which is now held in the lowered position, and hence to the main frame. The entire machine is accordingly drawn over the ground, the rear end being 20 supported by the wheels 33, while its forward end is supported by the draft bar 93. The bottom 46 of the scraping element is now in a position to contact with the ground, and scrape the earth, which is accumulated there- 25 in. When it is desired to stop this scraping motion, the operator pulls upon the line or cable 112, sufficiently to operate the lever 74 without operating the lever 61. The lever 74 thus has its lower end swung rearwardly, 30 and the head 69 of the latch 68 is moved from above the roller 70. The pull upon the elements 97, is now forwardly, as the draw-bar 31 is capable of moving forwardly in a longitudinal direction. This forward pull 35 swings the levers 98 forwardly, and the pull elements 101 are shifted forwardly, moving the scraping and supplemental frame forwardly. The rollers 53 now travel forwardly up the inclined portions 45' of the tracks 44, 40 whereby the forward portion of the supplemental frame is elevated, and the bottom of the scraping element moved upwardly out of engagement with the ground, and the scraping action stopped. The forward movement 45 of the supplemental frame 39 is limited by the bolts or stops 87, adapted to be mounted in selected openings 89 in the beams 40, contacting with the sides or plates 38 of the castings 35. When the draw-bar 31 is moved 50 forwardly, as above described, the wheel 25 traveling upon the inclined face 31' (the draw-bar being held stationary) tilts the main frame of the machine rearwardly, upon the axle 32, which in turn will tilt the scraper 55 rearwardly, to some extent, making it easy to carry the load a long distance, to the desired point, without liability of spilling the same. The invention is not restricted to the use of the tapered draw-bar with the inclined 60 face, as the inclined face may be dispensed with, if desired. I also contemplate using the inclined face of the draw-bar and associated elements, as the sole means for moving the forward end of the scraper out of 65 contact with the ground, prior to transport-

ing the load. The machine may now be conveyed to the desired point to dump the earth, and the cable 112 is now pulled sufficiently to operate the lever 61, the lower end of which is shifted rearwardly, and the bolt 55 70 is drawn from the opening 58. The weight of the dirt upon the bottom 46 swings the bottom downwardly and the dirt is discharged from the scraping element. The scraping element now automatically returns 75 to its horizontal position and the bolt 55 again enters the opening 58, locking the scraping element against turning movement upon its pivot. The supplemental frame is returned to its lowered rear position by pulling upon the lever 108, the returning movement being aided by the weight of the supplemental frame. It is thus seen that the filling and dumping of the scraping element is effected entirely through the pull trans- 80 mitted to and from the draw-bar, and no 85 clutches, gears, or the like are employed.

It is to be understood that the form of my invention herewith shown and described is to be taken as a preferred example of the 90 same, and that various changes in the shape, size, and arrangements of parts may be resorted to without departing from the spirit of my invention or the scope of the subjoined claims.

Having thus described my invention, I 95 claim:

1. In a machine of the character described, a main frame, wheels supporting the same, a supplemental frame, means whereby 100 the supplemental frame has a portion thereof supported by the main frame and is adapted to move longitudinally and upwardly with relation to the main frame, a scraping element supported by the supplemental frame, tracks secured to the main frame and having inclined portions, elements carried by the supplemental frame and arranged to engage the inclined portions of the track, a draft device connected with the 110 main frame and adapted to move longitudinally with relation thereto, connecting means between the draft device and the supplemental frame, and means to prevent the upward movement of the supplemental frame 115 with relation to the main frame.

2. In a machine of the character described, a main frame, wheels supporting the same, a supplemental frame extending longitudinally of the main frame, supporting 120 means carried by the main frame and engaging the rear portion of the supplemental frame, tracks secured to the main frame and having inclined portions, a scraping element provided at its ends with pivot shafts, 125 brackets secured to the supplemental frame and pivotally receiving the pivot shafts, wheels carried by the pivot shafts and engaging with the inclined portions of said tracks, a draft device secured to the main 130

frame and movable longitudinally with relation thereto, connecting means between the draft device and supplemental frame, and means to normally prevent the upward 5 movement of the supplemental frame with relation to the main frame.

3. In a machine of the character described, a main frame, wheels supporting the same, a supplemental frame extending longitudinally of the main frame, supporting means carried by the main frame and engaging the rear portion of the supplemental frame, tracks secured to the main frame and having inclined portions, a scraping element provided at its ends with pivot shafts, brackets secured to the supplemental frame and pivotally receiving the pivot shafts, wheels carried by the pivot shafts and engaging with the inclined portions of said tracks, a draft 20 device secured to the main frame and movable longitudinally with relation thereto, pull elements connected with the ends of the scraping element, and means connecting the pull elements with the draft device.

25 4. In a machine of the character described, a main frame, wheels supporting the same, a supplemental frame extending longitudinally of the main frame, supporting means connecting the supplemental frame and main 30 frame, tracks secured to the main frame and having inclined portions, wheels connected with the supplemental frame and engaging said inclined portions, a scraping element pivotally connected with the supplemental 35 frame, levers having their outer ends pivotally connected with the main frame, pull elements connected with said levers between their ends and connected with the ends of the scraping element, a draft device connected with the main frame and movable longitudinally thereof, and pull elements connected with the draft device and with the inner ends of said levers.

5. In a machine of the character described, 45 a main frame, wheels supporting the same, a supplemental frame extending longitudinally of the main frame, supporting means connecting the supplemental frame and main frame, tracks secured to the main frame and 50 having inclined portions, wheels connected with the supplemental frame and engaging said inclined portions, a scraping element pivotally connected with the supporting

frame, levers having their outer ends pivotally connected with the main frame, pull elements connected with said levers between their ends and connected with the ends of the scraping element, a draft device connected with the main frame and movable longitudinally thereof, a lever pivoted between its 60 ends upon the draft device, pull elements connected with the ends of the last named lever and with the inner ends of the first named levers, and means to prevent upward movement of the supplemental frame. 65

6. In a machine of the character described, a main frame, wheels supporting the same, a supplemental frame extending longitudinally of the main frame, supporting means connecting the supplemental frame and the 70 main frame, tracks secured to the main frame and having inclined portions, wheels connected with the supplemental frame and engaging the inclined portions of the tracks, a scraping element carried by the supporting 75 frame, a draw-bar connected with the forward end of the main frame and adapted to move longitudinally with relation thereto and having an inclined face, wheels carried by the main frame and engaging the draw-bar, one wheel engaging the inclined face whereby the main frame is adapted to be tilted upon its transverse axis when the draw-bar moves longitudinally with relation to the main frame, connecting means between the draw-bar and the supplemental frame, and means to hold the supplemental frame against upward movement with relation to the main frame. 80

7. In a machine of the character described, 90 a main frame, wheels supporting the same, a scraper carried by the main frame and extending transversely thereof, a draw-bar arranged at the forward end of the main frame and extending longitudinally thereof and having an upper inclined face, wheels connected with the main frame and engaging the longitudinal faces of the draw-bar, a supporting element to which the draw-bar is connected, and means to control the longitudinal movement of the draw-bar with relation to the main frame. 95 100

In testimony whereof I affix my signature.

FREDRICK R. MORTON.
